(57) **CLAIM**

The ornamental design for a shoulder-mounted beverage holder, as shown and described.

DESCRIPTION

This application claims the benefit of U.S. patent application Ser. No. 11/318,036, filed Dec. 23, 2005, pending.

FIG. 1 is a perspective view of a shoulder-mounted beverage holder.

FIG. 2 is a side view of the shoulder-mounted beverage holder of FIG. 1, showing the adjustable fasteners in slots at the bottom of the harness.

FIG. 3 is a top view of the tray layout of the shoulder-mounted beverage holder of FIG. 1; and,

FIG. 4 is a cross-sectional view of the shoulder-mounted beverage holder of FIG. 1 along the line 4-4'.
